UNITED STATES PATENT OFFICE.

JULIUS KAHN, OF DETROIT, MICHIGAN, AND THOMAS HENRY KANE, OF YOUNGSTOWN, OHIO.

STRUCTURAL MEMBER.

1,085,429.

Specification of Letters Patent.

Patented Jan. 27, 1914.

Application filed September 26, 1913. Serial No. 791,815.

To all whom it may concern:

Be it known that we, JULIUS KAHN, a citizen of the United States, residing at Detroit, in the county of Wayne and State of Michigan, and THOMAS H. KANE, a citizen of the United States, residing at Youngstown, in the county of Mahoning and State of Ohio, have invented a new and useful Structural Member, of which the following is a specification.

This invention relates to structural members, such as columns, girders and beams, which are constructed by uniting a plurality of rolled bars, and its object is to provide built-up members which are so constructed by rolling down properly formed flanges of each of the bars onto adjacent portions of other bars that the various bars shall be rigidly locked together.

This invention consists in a structural member consisting of a flat web member having an enlarged longitudinal edge and laterally extending flanges adjacent such enlargement, and an edge plate at substantially right angles to the web member and having parallel longitudinal flanges along the middle of one side, spaced to receive the enlarged edge of the web member, said parallel flanges being bent to fit around said enlargement, and the flanges of the web being bent flat against the edge portions of the parallel flanges to lock them in position.

In the accompanying drawing, Figure 1 is a perspective of this improved structural member. Fig. 2 is an end view of the web member before the flanges are bent. Fig. 3 is an end view of the bar forming the edge plates of the structure.

Similar reference characters refer to like parts throughout the several views.

Beams and columns have been constructed with web members having enlarged edges, combined with flanged plates extending along the edges of the web members and having their flanges bent around the enlarged edges. This type of construction is objectionable in many cases because the flanges are liable to bend away from the web members. The present structure prevents such separation by means of auxiliary flanges on the web members which are folded down onto the flanges of the edge plates, preventing them from separating from the

web and thus, in effect, constituting with such flanges a double lock between the members.

The web members and side plates may be rolled out in the form of bars having cross sections such as shown in Figs. 2 and 3. The web 1 may have enlarged edges 2 and flanges 3. The side plates 4 may have flanges 5 spaced to receive the enlarged edges 2, and if desired, the edge flanges 6. When a beam or column is to be constructed, the parts 2 of the web members are placed between the flanges 5, and these flanges are bent to fit around the enlargements, as shown in Fig. 1. After this, the flanges 3 are bent down parallel to each other onto the outer edges of the flanges 5. It is apparent that a T beam may be constructed by uniting a web member and one of the side plates, and that the use of two side plates will produce an I beam, or that such structure may be used as a column.

The stress to separate the flanges 5 and the web 1 is greatest near the line of connection between these flanges and the plate 4, and therefore, the effect of the engagement of the flanges 3 with the outer edges of the flanges 5 will be most advantageous because of the leverage due to the distance from the plate 4. The resultant structure is one of great stiffness and the various parts are rigidly locked together. When the structural member is to be used as a beam, the flanges 6 may be omitted. The sizes and proportions of the various parts may be modified by engineers as found desirable, without departing from the spirit of our invention.

We claim:

1. In a structural member, the combination of a web member having enlarged edges and flanges adjacent such enlarged edges, and edge plates having flanges extending along the enlarged edges and bent down onto said edges, the flanges of the web member being bent to engage the flanges on the edge plates.

2. In a structural member, the combination of a web member having an enlarged edge and longitudinal lateral flanges, and an edge plate having parallel longitudinal flanges between which such enlargement extends, the parallel flanges of the edge plate being bent to fit around said enlargement.

and the flanges on the web member being bent to lie against the edges of the parallel flanges.

3. In a structural member, the combination of a central member comprising a plate having parallel enlarged edges and pairs of laterally extending flanges adjacent said edges, and a pair of side members at right angles to the central member, each comprising a plate having parallel flanges extending from one side and spaced to receive the enlarged edges of the central member, the parallel flanges of the side members being bent to fit around the enlarged edges of the central member and the flanges of the central member being bent down parallel to each other against the flanges of the side members.
4. In a structural member, the combination of a central member comprising a web plate, rectangular ribs along the edges thereof, and pairs of laterally extending flanges

adjacent and parallel to the ribs, and a pair of side plates at right angles to the central member, each having a pair of parallel flanges fitting around the ribs and having their edges in engagement with the web plate, the flanges of the central member being bent to engage those adjacent portions of the flanges of the side plates that fit against the web plates.

In testimony whereof we have each signed this specification in the presence of two subscribing witnesses.

JULIUS KAHN.

THOMAS HENRY KANE.
